UNITED STATES PATENT OFFICE

WILLIAM J. CROSS, OF ANN ARBOR, MICHIGAN

SANDING DEVICE

Application filed March 7, 1929. Serial No. 345,095.

The present invention relates to improvements in sanding devices and more particularly to one designed for use in connection with motor vehicles.

5 The primary object of the invention is to provide a device of this character adapted to be placed upon a motor vehicle, the construction being such that sand or other material is discharged in advance of the rear wheels 10 of the vehicle to prevent skidding or to obtain traction when stalled or on slippery roads or streets.

Another object of the invention is to provide a device of this character so constructed 15 that it can be quickly placed in operation by the driver of the car.

Another object of the invention is to provide a device of this character so constructed that upon swinging an actuating lever the 20 contents of the hopper will be discharged into chutes and from thence to points in advance of the rear wheels of the vehicle.

With these and other objects in view, this invention resides in the novel features of construction, formation, combination and arrangement of parts to be hereinafter more fully described, claimed, and illustrated in the accompanying drawings, in which:

Figure 1 is a view of a motor vehicle, showing the position of the device with respect thereto.

Figure 2 is a sectional view on the line 2—2 of Figure 3.

Figure 3 is a fragmentary bottom plan 35 view.

Figure 4 is a transverse sectional view.

Referring to the drawings, 1 designates a hopper which is mounted under the front seat 2 of the vehicle or in any other convenient 40 location. The floor board 3 of the vehicle provides a bottom for the hopper and has formed therein a pair of discharge openings 4.

Chutes 5 are secured to the under surface of 45 the board 3 and have openings 5' formed in their front sides, said chutes being disposed directly under the openings 4 so that the sand passing through said openings will gravitate into the chute. Each chute has connected 50 thereto a hose 6 which has its discharge end

located in advance of a rear wheel so that the material discharged will be distributed properly for effective operation. It will, of course, be understood that steel tubing may be used in lieu of the hose, if found more desirable. 55

Fixed to the under surface of the board 3 are blocks 7 which have secured thereto metal plates 8, and pivotally connected to said metal plates are metal plates 9, the latter 60 plates having blocks 10 carried thereby. The plates 8 and 9 have associated therewith the terminals of coil springs 11 which are arranged to surround the pivotal rods 12 of the plates. By providing the springs the same act to hold the blocks normally flush against the under surface of the floor board 3 so as to close the openings 4, thus preventing leakage of sand from the 65 hopper 1. The forward ends of the plates 9 are provided with arms 13 and to which are connected the rear ends of the cables 14, said cables being disposed in diverging relation 70 and having their forward ends secured to a turnbuckle 15, said turnbuckle being pivoted to the crank 16 formed upon the lower end of the shaft 17. The shaft 17 is journaled in the floor board and extends upwardly and adjacent the front wall of the seat 2. The upper end of the shaft 17 is provided with a handle 75 18 to facilitate rotation of the shaft so that the crank arm will be shifted to pull upon the cables 14, which action will swing the blocks 10 downwardly so that the contents of the 80 hopper will discharge into the chutes. The shaft 17 is journaled in a suitable bracket 19. 85

Fixed upon the floor board 3 adjacent the crank 16 is a stop 20 which is adapted to limit the swinging movement of the crank 16 when the same is swung to open the openings 4, said stop holding the shaft 17 in a position slightly past dead center. In this manner, the blocks can be held in their open position until the rotation of the shaft is reversed, and after which the springs 11 will cause the blocks 10 to move to position to close the 90 openings 4. These blocks have mounted thereon pins 21 which serve to prevent clogging of the openings 4. 95

Mounted in the hopper and located be- 100

tween the openings 4, is a deflector 22 which will obviously serve to direct the contents of the hopper toward said openings.

From the foregoing, it is thought that the construction, operation, and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

What is claimed is:

- 15 1. A sanding device for motor vehicles comprising a hopper mounted upon the floor of the vehicle, chutes fixed to the floor below the hopper, said floor having openings therein for discharging sand from the hopper into the chutes, blocks pivotally connected with the floor for normally closing the openings, a shaft supported by the vehicle, and means connecting the shaft and blocks for swinging the blocks open to permit passage of sand 25 through the openings into the chutes, and means for discharging sand from the chutes. 80
- 20 2. A sanding device for motor vehicles comprising a hopper, chutes fixed to the floor of the vehicle below the hopper, said floor having openings therein affording communication between the hopper and chutes, blocks pivotally connected with the floor for normally closing the openings, a shaft carried by the vehicle, a turnbuckle connected to the 30 shaft, cables connecting the turnbuckle and blocks, said blocks being swingable to permit sand to pass through the openings into the chutes upon actuation of the shaft. 85
- 25 3. A sanding device for motor vehicles comprising a hopper, chutes fixed to the floor of the vehicle, said floor having openings therein, blocks pivotally connected with the floor, means for yieldably holding the blocks in position to close the openings, a shaft rotatably supported by the vehicle and having a crank upon its lower end, a turnbuckle connected to the crank, and cables connecting the turnbuckle and blocks to swing the blocks open upon actuation of the crank. 95
- 30 4. A sanding device for motor vehicles comprising a hopper mounted upon the floor of the vehicle, chutes fixed to the floor, said floor having openings therein affording communication between the hopper and chutes, blocks normally closing the openings, plates fixed to the blocks, said plates being pivotally and yieldably connected with the floor, said plates having arms, a shaft rotatably mounted upon the vehicle, a crank carried by the shaft, and means connecting the crank and arms for swinging the blocks open upon actuation of the crank. 100
- 35 5. A sanding device comprising a hopper having discharge openings, blocks normally closing the openings, chutes below the hopper, 105

said blocks having pins carried thereby for engagement in the openings to prevent clogging thereof, and means for swinging the blocks to open position to permit discharge of sand from the hopper through the openings into the chutes. 70

In testimony whereof I affix my signature.

WILLIAM J. CROSS. [L.S.]
